(57) **CLAIM**

The ornamental design for a display screen with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first embodiment for a display screen with graphical user interface;

FIG. 2 is a front view of a second embodiment for a display screen with graphical user interface;

FIG. 3 is a front view of a third embodiment for a display screen with graphical user interface; and,

FIG. 4 is a front view of a fourth embodiment for a display screen with graphical user interface.

The broken line showing of a display screen with graphical user interface in all views is included for the purpose of illustrating portions of the article and form no part of the claimed design.

1 Claim, 4 Drawing Sheets

(4 of 4 Drawing Sheet(s) Filed in Color)
